HINGED CARD

Albert A. Ainsworth, Ossining, N. Y.

Application November 25, 1933, Serial No. 699,780

6 Claims. (Cl. 129—19)

The invention relates to the art of filing cards, photographs or other comparatively stiff articles, and as to many of its features is an improvement on the inventions covered by my prior Patents Nos. 1,461,570, dated July 10, 1923, and 1,862,450, dated June 7, 1932.

In common with my Patent No. 1,862,450, I prefer to employ a backing or folder of comparatively stiff material having one or more strips of tough flexible material secured to the backing and having flexible hinged tongues or other means for adhesively retaining the articles to be filed. Each of the strips of flexible material may carry a battery of hinges for mounting a plurality of cards, or, if desired, individual hinges for each card may be provided, preferably arranged in vertical rows.

I have found that when cards, photographs or other relatively stiff articles are mounted in the manner described in my prior patents, there is a tendency for the edges of such cards, etc. to catch or buckle as they are turned back on their hinges. One object of the present invention is accordingly to provide relatively stiff cards which are especially adapted for use with my filing system and which may be readily turned over on the relatively flexible bases to which they are attached without buckling or catching.

It is sometimes desirable in mounting photographs, samples, cards and the like to provide means whereby they may be removed from the file and replaced when desired, or replaced by new samples, cards, photographs, etc. Therefore, according to its preferred embodiment, my invention contemplates the use of major or backing cards or the like to which minor cards, samples or the like may be detachably secured, the major cards being secured within the folder by means of the flexible hinges.

Other objects of the invention will be apparent from a consideration of the following detailed description and accompanying drawings setting forth illustrative embodiments of the invention.

In the drawings,

Fig. 1 is a view of the front or inside face of a backing or folder having major cards or slips hingedly secured thereto by means of gummed strips, and minor slips or cards removably attached to the major slips;

Fig. 2 is a lengthwise section on line 2—2 of Fig. 1;

Fig. 3 is a fragmentary section on an enlarged scale showing a portion of Fig. 2 and indicating the manner of attaching the major cards;

Fig. 4 is a rear view of the gummed strip forming one element of Fig. 1;

Fig. 5 is a plan view showing a major card for attachment to a suitable backing, the card having a minor card attached thereto and being provided with projections and cut-away portions on the filing edge for preventing buckling in turning the card;

Fig. 6 shows a card wherein the projections are gummed;

Fig. 7 shows a modified card in which separate gummed members are applied to the major card to facilitate attachment to the flexible tabs;

Fig. 8 is a detail sectional view showing one of the gummed members applied to the card;

Fig. 9 is a perspective view of one of the gummed members;

Fig. 10 shows a modified form of major card provided with cut-away portions to facilitate mounting of the minor card;

Fig. 11 shows a minor card adapted for attachment to the major card illustrated in Fig. 10 in the manner shown in Fig. 13;

Fig. 12 shows an open album on the pages of which the assembled major and minor cards of Fig. 13 are shown mounted by means of a battery of the separate hinges shown in Fig. 14;

Fig. 13 shows the major and minor cards of Figs. 10 and 11 in assembled position, and

Fig. 14 is a detail view showing a flexible gummed strip provided with a plurality of tongues, and adapted to serve as a hinge for one or more cards to be mounted on a backing.

According to the preferred embodiment of my invention, a suitable backing 10 (Figs. 1, 2, 3, and 12) is employed composed of comparatively stiff material which may constitute one or both covers of an album or other filing folder, and to the backing are adhesively secured one or more strips of flexible material having gummed portions accessible for mounting one or more bills, slips, cards, photographs, or other articles thereon, in accordance with the teaching of my prior Patent No. 1,862,450. If desired, the strips of flexible material 11 may be provided with batteries of flexible hinged tongues 12 for mounting the cards, etc., 13 in overlapping order, such tongues being formed in rows in a single strip, as shown in Figs. 1, 2, 3, and 4, wherein two parallel rows of incisions are formed in the strip 11. Obviously any number of strips may be employed, each adapted for mounting any desired number of cards, etc., according to the requirements of each individual case. If desired, flexible tongues 12 may be formed directly in the backing 10 without the use of the strip 11.

As shown in Fig. 12, the backing 10 is hinged

along the line $x-x$, and is provided with vertical and horizontal guide lines such as are shown in my Patent No. 1,862,450, which insure the proper locating of flexible strips $11a$ (shown in detail in Fig. 14), each carrying two or more tongues or hinges 12 , each strip being primarily intended for mounting a single card, though obviously three smaller cards, bills or the like may be mounted by the use of the three tongues 12 . In mounting the strips $11a$ on the backing 10 , the gummed portion of the body $11b$ of the strip only is secured to the backing, leaving the gummed under portion of the tongues accessible for the mounting of cards, photographs, etc. When a number of the individual flexible strips with cards mounted thereon are assembled in vertical alignment, as indicated in Fig. 12, the composite album is substantially identical with that illustrated in Figs. 1 to 3, the individual strips being contiguous to each other and forming a single strip provided with batteries of gummed tongues, each set of tongues being adapted to carry one or more cards 13 , which cards in the assembly are arranged in overlapping order. The individual hinging strips with the tongues carried thereby may be readily manufactured by first forming a single gummed strip similar to that shown in Fig. 4 with tongues gummed on one side formed by incisions made through the strip, and then cutting the composite strip into the desired number of individual strips. In such case, however, the tongues cut in the initial composite strip should be spaced somewhat farther apart in the vertical rows in order to provide body portions for the individual strips cut therefrom. As shown on the left-hand leaf of the backing in Fig. 12, the individual strips are mounted with the points of the tongues downward and the cards are initially mounted from the lower side of the backing, whereas on the right-hand leaf of the album the strips are initially mounted with the tongues pointing upwardly, in which case the cards are mounted from above and are then reversed together with the hinged tongues.

Slips, cards, photographs and the like 13 are adapted to be secured to the tongues 12 in overlapping order. Each of the underlying cards extends beyond the card above it and this extension provides space for identification of the card or slip. In order to prevent buckling of the cards 13 in turning the same on their hinges provided by the tongues 12 , the edge of the card to be secured to the tongues is provided with cut-away portions leaving projections 14 corresponding in number to the number of rows of tongues 12 . The purpose of this arrangement is to prevent the card or slip from buckling or catching during turning when the card or slip is filed snugly into the tongues for proper alignment of the cards. By cutting away the edge of the card intermediate the projections 14 , too close filing is prevented and friction in turning the leaves is avoided entirely.

In securing the cards 13 to the tongues 12 , either the tongues may be gummed as indicated in Figs. 1 and 4, or the cards may be provided with gummed portions corresponding with the tongues, in which case it is not necessary to provide adhesive on the tongues.

In Fig. 6 cards are shown having adhesive applied directly thereto, which, it will be noted, covers the projections 14 . In Fig. 7 a card is shown in which triangular members 16 having

adhesive on both sides thereof are attached to the card. Obviously the cards may be filed with either the long side or the short side uppermost without departing from my invention.

As shown in Fig. 1 the major cards 13 are provided at their upper portions and at the sides with "thumb nail" slots 17 under which may be removably mounted minor cards 18 , which may be photographs, papers, samples of linens, silks, etc. The mounting is such that the minor cards, etc. may be taken out at will and others put in their places. This arrangement is much less expensive than where the samples are permanently fastened under the gummed tabs or hinges 12 , thereby necessitating a new filing folder or device whenever changes are necessary.

In the embodiment of the invention shown in Fig. 1, the thumb nail slots are omitted at the bottom of the card 13 , thus permitting the minor card to be slid lengthwise and removed. In the embodiment of the invention disclosed in Fig. 5, the slots are provided on all four sides of the card, thus providing a more permanent mounting.

In the embodiment of the invention shown in Fig. 7, the major card 13 is intended as a sample carrier, and is provided with a plurality of apertures 19 , while the minor card 18 is provided with projecting members 20 which extend through slots 21 in the major cards and show through the apertures 19 .

Upon the projections 20 suitable designations such as dates, prices, costs, or other vital data may be printed or written so that this information will be readily visible through the apertures 19 . The reference numeral 22 denotes a sample of goods, or the like, in reference to which the designations appearing on the members 20 have a vital bearing.

In the embodiment of the invention disclosed in Figs. 10, 11, 12, and 13, the major card 13 is provided with especially formed cut-away portions $25, 25$ near the top and somewhat similar but preferably larger cut-away portions $26, 26$ near the bottom to facilitate mounting of the minor card 18 , much more readily than in the embodiments of the invention heretofore disclosed. These peculiarly shaped cut-away portions 25 and 26 of card 13 coact to automatically force the card 18 down to the points of the cut-away portions, thereby bringing the lower edge of the card 18 exactly even with the lower edge of card 13 , which is important in the mounting of such cards, so that when mounted there will be visible a uniform portion of all cards so mounted, as shown in the drawings. This visible portion may be wide or narrow in accordance with the necessity for the visible space on the bottom of each mounted card 18 and such variations of widths of the visible space are regulated by the positions of the cut-away portions of card 13 .

Those portions of the cut-away parts 26 of card 13 designated $28, 28$ and $29, 29$, being cut on an incline, force the card 18 down to its proper alignment with the bottom of card 13 and will not allow it to go farther than this exact alignment.

This method of mounting the minor card 18 on the major card 13 is more easily accomplished than in other embodiments of the invention, due to the fact that the cut-away portions 25 and 26 of card 13 permit the corners of card 18 to be easily engaged in such cut-away portions.

Card 13 , being permanently mounted in the hinged backing 10 , forms the desired vehicle to

carry card 18 in true alignment in an efficient manner, and at the same time permits of the removal of card 18 at any time or for any purpose, and the insertion in the same card 13 of a new card 18.

Card 18, in order to fit properly into the cut-away portions 26, 26 of card 13, is also cut away as shown in two places 27, 27. These portions 27, 27, when engaged in the cut-away portions 26, 26 of card 13, with the corners 30, 30 of the card 18 also properly engaged in the cut-away portions 25, 25 of card 13, automatically bring the bottom line 31 of card 18 into perfect alignment with the bottom line 32 of card 13.

It is thus a part of my invention that the major card 13, as shown, forms an efficient and easily engaged carrier for card 18, which is also easily removed or exchanged for a new card or a card carrying different data.

Various embodiments of the invention have been described in detail for the purpose of illustration, but it will be understood that in each embodiment herein disclosed base cards are permanently mounted on a backing in such a manner as to swing freely about specially constructed hinges, while secondary cards may be quickly and easily mounted in the base cards and firmly held in that position until it becomes necessary for their removal which must also be accomplished with ease and quickness. It will be further understood that the various individual features of novelty described in conjunction with the broad combination likewise form part of my invention.

What I claim is:

1. A filing device comprising a backing having a plurality of relatively flexible holding tabs, and a relatively stiff card adapted to be secured to said tabs and having means inserted snugly into the roots of said tabs for preventing buckling

between the card and backing when the same is turned over.

2. A device as set forth in claim 1, wherein the filing edge of the card is cut away except for projections corresponding in number and location with the leaf holding tabs.

3. In a device of the character described, a relatively stiff filing card having a plurality of projections on the filing edge with intermediate cut-away portions, the projections being gummed for attachment to suitable relatively flexible leaf holding tabs which serve as hinges when the card is turned over.

4. A filing device comprising a backing having relatively flexible leaf-holding tabs, a relatively stiff leaf or card adapted to be secured to said tabs and having means for preventing buckling when the card is turned over, said means comprising projections on the filing edge of the card for engagement with each of the card holding tabs at the bases thereof, said cards having cut-away portions between said tabs and projections being adhesively secured together.

5. A filing device as set forth in claim 1, wherein in the card is provided with gummed projections corresponding in number and location with the leaf holding tongues, the intermediate portions of the filing edge being cut away.

6. A filing device comprising a stiff backing, a strip of tough flexible material gummed thereon having projecting tabs accessible for filing purposes, and a relatively stiff leaf or card secured snugly in the angle between said backing and said tabs, the major portion of the filing edge of which is spaced away from the backing to prevent buckling between the card and backing as the card is turned over, with the flexible tabs serving as hinges.

ALBERT A. AINSWORTH.
